The ornamental design for a lever actuator, as shown and described.

DESCRIPTION

FIG. 1 is a perspective view of a lever actuator showing my new design;
FIG. 2 is a top plan view thereof;
FIG. 3 is a bottom plan view thereof;
FIG. 4 is a side elevational view thereof, the opposite side elevational view being a mirror image;
FIG. 5 is a front elevational view thereof; and,
FIG. 6 is a rear elevational view thereof.

FIG. 1

FIG. 2

FIG. 3

FIG. 4

FIG. 5

FIG. 6
